UNITED STATES PATENT OFFICE

90,578

DESIGN FOR A LAUNDRY TUB RIM

Robert S. Grogan, Chicago, Ill.

Application July 8, 1933. Serial No. 48,663

Term of patent 14 years

To all whom it may concern:

Be it known that I, ROBERT S. GROGAN, a citizen of the United States, residing at Chicago, in the county of Cook and State of Illinois, have invented a new, original, and ornamental Design for a Laundry Tub Rim, of which the following is a specification, reference being had to the accompanying drawing, forming part thereof, in which—

Fig. 1 is a perspective view of a laundry tub rim showing my new design.

Fig. 2 is an enlarged detail showing a portion of the rim.

Fig. 3 is an enlarged section taken on the line 3—3 of Fig. 1.

I claim:

The ornamental design for a laundry tube rim as shown.

ROBERT S. GROGAN.
